TALBOT G. MARTIN, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC PRIVATE-BRANCH-EXCHANGE TELEPHONE SYSTEM.

1,312,558.

Specification of Letters Patent.

Patented Aug. 12, 1919.

Application filed October 21, 1911, Serial No. 655,985. Renewed May 17, 1919. Serial No. 297,957.

To all whom it may concern:

Be it known that I, TALBOT G. MARTIN, a citizen of the United States of America, and resident of Chicago, Cook county, Illinois, have invented a certain new and useful Improvement in Automatic Private-Branch-Exchange Telephone Systems, of which the following is a specification.

My invention relates to automatic telephone systems, and more particularly to telephone systems comprising a main automatic exchange and an automatic private branch exchange. In private branch exchange systems it is often desirable that the private branch exchange, which is usually represented by a single number, have a plurality of trunk lines, and by calling the number of this exchange an idle trunk line in a group is selected.

One of the objects of my invention is to provide an improved rotary selector, which selector is provided with a plurality of trunk terminals arranged in different levels, and two or more groups of trunk lines which extend to private branch exchanges terminating in the same level of this rotary selector. In connection with an automatic private branch exchange it is likewise necessary that this rotary selector be provided with means for repeating impulses in order to extend the call through this branch exchange. This rotary selector operates in a manner similar to that of a rotary connector—that is, after the wipers have been raised to any level by impulses representing one digit, they do not begin to rotate automatically as in the ordinary selector switch; but in response to the impulses for the second digit, the wipers are rotated on to the contacts corresponding to that digit. If the first of the group of contacts corresponding to this digit is busy, the wipers will be automatically rotated to an idle contact. Among the novel features of this switch is the provision of two private banks of contacts and two private or testing wipers. The guarding potential on the contact of one of these banks will cause the contact arms to rotate past the corresponding trunk, while a guarding potential upon both contacts will cause the arms to stop upon that trunk, but will prevent the completion of the talking circuit.

These and other objects of my invention will be more clearly understood by reference to the accompanying drawings, in which—

Figures 1, 2 and 3 show a complete connection between a calling substation A and a called substation A' in a system embodying the principles of my invention.

The line of the calling substation A terminates in a main automatic exchange, while the substation A' is located at a small branch exchange. The main automatic exchange is a well-known type comprising subscribers' individual or line switches, selectors and connectors. The branch exchange comprises subscribers' individual switches, selectors and connectors. The connection shown is extended through the subscriber's individual switch C, a first selector E and a combined selector and repeater F at the main exchange to a trunk line leading to a connector H at the branch exchange, through the medium of which the connection is completed with the called line. The selector-repeater F is preferably used exclusively for calling branch exchanges and it, together with a number of other similar switches, is accessible through some particular level of the first selectors E. The remaining levels of the first selectors may be connected with ordinary second selectors in the usual manner for the purpose of extending connection through the main exchange to subscribers' lines which terminate directly therein. At L (Fig. 3) there is shown a ringing current generator and at M, M' and M² busy signaling machines are represented. Each exchange is shown provided with a battery B for supplying current for operating the central office switches and for talking purposes.

The automatic substations may be of any suitable or approved type. As shown herein, the substation A comprises the usual receiver 2, transmitter 3, switch hook 4, ringer 5 and condenser 6. Since it is an automatic substation, it is also provided with an automatic calling device of the well-known type comprising a pair of impulse springs 7 and 8 and a toothed impulse wheel 9, which latter is controlled by the subscriber through the medium of a dial (not shown) provided with finger holes. The mechanism is so arranged that as the dial and impulse wheel are rotated forward by the subscriber, the impulse springs are not operated; but as the dial returns to normal position, said springs are separated momentarily a number of times, corresponding to the digit called. In order to prevent the resistance of the sub-

station apparatus from interfering with the efficient operation of the relays at the central office, there is secured to the same shaft to which the impulse wheel 9 is secured an arm 197 which, whenever the dial and impulse wheel are turned, permits the spring 198 to engage the spring 199. The engagement of these springs establishes a short-circuit around the transmitter and receiver, and since this short-circuit endures as long as the impulse springs 7 and 8 are being operated to transmit impulses to the central office, said impulses are prevented from passing through the receiver and transmitter at the substation. When the impulse wheel returns to normal position, and after the last impulse is delivered to the central office, the arm 197 separates the springs 198 and 199 to restore the receiver and transmitter to operative condition for talking.

The line switch C and the master switch D are of the general type of line and master switches disclosed in British Patent No. 26,301, of 1906, to R. W. James, but are of the particular form shown in British patent to T. G. Martin, No. 1419 of 1910. As herein represented the line switch C comprises, among other details, a plunger (not shown) which is attached to the end of a so-called plunger arm 10, which latter is controlled by the plural-wound magnet 11. Besides controlling the plunger arm 10, the magnet 11 also controls the relay armatures 12 and 13 and comprises four windings, namely, a pull-in winding 14, a holding or cut-off winding 15, a line winding 16 and an auxiliary winding 17. The lateral projection 18, near the center of the core of the magnet and by means of which said magnet is mounted upon the bracket 19, divides the magnetic circuit of the magnet into two parts, so that the windings upon one end of the core do not have any effect upon the armatures on the other end. Of the two windings upon the upper end of the magnet, only the winding 14 is strong enough to attract the plunger arm 10 from its normal position. Although the winding 15 is not strong enough to operate the arm 10, it is strong enough to hold it in its operated position after it has once been pulled down. When the plunger arm 10 is attracted by the magnet 11, the plunger of the switch is forced into a group of contact springs 20, 21, 22, 23, 24, 25, 26 and 27, forcing them into contact in pairs. Although only one set of springs 20-27 is shown, each switch is provided with a plurality of such sets, each set forming a terminal of a separate trunk line leading to a selector E. Each trunk line is multiplied through the corresponding contacts of all the switches of a group which is controlled by the master switch D, while the line conductors of the substation A are con-

nected in multiple to the springs 20 and 22 of all of the different sets in its own switch. The plungers of all the line switches of the group which is controlled by the master switch D engage a so-called plunger shaft (not shown), and through the medium of said master switch are normally maintained opposite the terminals of an idle trunk line. The master switch consists essentially of a motor magnet 28 for rotating the ratchet wheel 29. The ratchet wheel 29 is connected with the plunger shaft in such manner that a rotary motion of the ratchet wheel gives to the plunger shaft a reciprocating motion to carry the idle plungers back and forth in front of their trunk terminals. To the plunger shaft there is secured a locking plate 30 provided near its outer edge with a number of openings which are adapted to be engaged by a pin 31 upon the end of the armature 32 of the relay 33. The openings in the plate 30 are so spaced that the pin 31 can engage one of them and allow the armature 32 to resume its normal position only when the plungers of the idle line switches are directly opposite the terminals of a trunk line. The master switch is also provided with a bank of contacts comprising a common segment 34 and an individual contact *a* for each trunk line to which the line switches have access. The wiper 35 always maintains the segment 34 in electrical connection with the individual contact *a* of the trunk line before which the plungers of the idle line switches are being held by the master switch.

The selector E is of the general type of selector switches disclosed in United States Letters Patent No. 815,321, granted to Keith, Erickson and Erickson March 13, 1906, the circuits being modified, however, as shown in British Patent No. 1419 of 1910 referred to above, in order to operate in a two-wire system—that is, a system in which the central office apparatus is controlled by the calling subscriber over the two sides of the line in series. As herein represented, the selector E comprises a bank of contacts arranged in rows or levels, which contacts are adapted to be engaged by a set of wipers 36, 37 and 38 carried upon a vertically and rotatably movable shaft (not shown) which is controlled by the so-called vertical and rotary magnets 39 and 40. The usual side switch comprising the wipers 41, 42, 43 and 44 is controlled by the private magnet 45 in a manner well known in the art. Means for restoring the switch to normal position are provided in the release magnet 46. In this instance the release magnet is adapted to restore the switch to normal position immediately upon energizing, as shown in United States Letters Patent No. 815,176, granted to Keith, Erickson and Erickson

March 13, 1906, for connector switches, rather than by deenergizing as shown in the selector patent hereinabove referred to. The springs 17 are permitted to engage only when 5 the switch shaft is raised one or more steps from its lowest or normal position. The operations of the switch are controlled by the calling subscriber through the medium of the double-wound line relay 48. The relays 49, 10 50 and 51 are slow-acting relays—that is, relays which deenergize slowly after their energizing circuits have been broken. The desired action of these relays may be accomplished by providing a ring of copper 15 around one end of the core. The contacts 52, 53 and 54 are assumed to be a set of contacts in the first level of the selector bank and are the terminals of a trunk line leading to the selector-repeater F. The contacts 20 55, 56 and 57 represent a set of contacts in the second level and form the terminals of a trunk line which may lead to an ordinary second selector.

The general construction of the selector-repeater F is practically the same as that of selector E, the selector-repeater F has four 25 eration, however, being somewhat different. Instead of only three wipers, as in the selector E, the selector-repeater has four 30 wipers, namely, the two line wipers 58 and 59 and two private or testing wipers 60 and 61. There is no third conductor in the trunk line leading to the connector H corresponding to the conductor 116 (Figs. 1 and 2), and 35 the contacts which are engaged by the wipers 60 and 61 are simply multiplied with the corresponding contacts in the banks of the other switches F which have access to the same trunk lines as the switch shown in 40 the drawings. The difference in the mode of operation of the selectors E and F is as follows: In the selector E the wipers are adapted to be raised to any level of the bank contacts by a certain number of impulses 45 transmitted through the line relay 48, and upon the cessation of these impulses the wipers are automatically rotated onto the first set of idle contacts in this level. Thus, in the selector E all of the trunk lines which 50 are connected to contacts in any given level are accessible by calling one digit. In the selector F the wipers are raised to any desired level by a number of impulses transmitted through the line relay 62 in practically 55 the same manner as in the selector E. The wipers of the selector F, however, do not begin to rotate automatically upon the cessation of the impulses through the line relay. After the wipers have been raised to 60 any desired level, they may be rotated onto any desired set of contacts in that level by another set of impulses through the line relay. Upon the cessation of this second set of impulses, the wipers of the selector F 65 will remain upon the contacts onto which

they have been rotated if the trunk line connected to these contacts is idle. If this trunk line is busy, however, the wipers will be automatically rotated off them, and will continue to rotate until the contacts of an idle 70 trunk line are reached, or until a point is reached where the contacts engaged by the two private wipers 60 and 61 are connected together. With this arrangement it will be evident that a plurality of groups of trunk 75 lines may be connected to each level of bank contacts of the selector F, and an idle line in any one of these groups may be selected by calling two digits upon the switch, these two digits corresponding to the position in 80 the bank of the first trunk line of the group. The contacts which are engaged by the wipers 60 and 61 and corresponding to the last trunk line in every group are connected together. When the wipers are searching 85 for an idle trunk and reach a position where the wipers 60 and 61 engage contacts which are thus connected together, the wipers will come to rest regardless of whether the trunk line is busy or idle. If the trunk line is 90 busy, no connection will be completed therewith when the wipers 58 and 59 come to rest upon its contacts. The selector F, besides acting as a selector, also acts as a repeater to receive impulses from the calling substation 95 and repeat them around the condensers 63 and 64 to the trunk line with which it has made connection. The line relay 62 is connected with the trunk conductors 65 and 66 through the contacts of a reversing relay 67. 100 This relay is provided with two windings 68 and 69, and it is necessary that both of these windings be energized and in the same direction before its armature will be operated. The means for automatically in- 105 terrupting the circuit of the rotary magnet 125 to cause the wipers to rotate in search of an idle trunk line comprises a relay 134, the circuit of which is controlled by the armature of the rotary magnet through the 110 medium of the contact 133.

The connector H is of the general type of connector switch disclosed in United States Letters Patent No. 815,176 previously referred to, but, like the selectors, is modified 115 to operate in a two-wire system. Like the selectors, the connector is provided with a shaft (not shown) carrying the wipers 70, 71 and 72 and controlled by the vertical and rotary magnets 73 and 74. The usual side 120 switch is controlled by the private magnet 75 in the usual manner. At 76 there is shown a ringing relay which is provided for the purpose of connecting the ringing current generator to the called line to signal the 125 called subscriber. The talking circuit through the connector is divided into two sections, which sections are inductively connected by the condensers 78 and 79.

The substation A' and the line switch C' 130

are in all respects the same as the substation A and the line switch C.

Having given a general description of the apparatus, it will now be explained in detail how the subscriber at substation A may obtain connection with the branch exchange substation A', the number of which latter will be assumed to be 155—20. The number 155 signifies the common number of a plurality of trunk lines leading to the branch exchange, while the number 20 signifies the number of the substation A' in the branch exchange. Thus, it has been assumed that the first trunk line of the group leading to the branch exchange to which the substation A' belongs is connected to the fifth set of contacts in the fifth level of the banks of the selector F. In the drawings it has been assumed that the trunk line shown is this first trunk, and that there are three trunk lines in the group. The private bank contacts of all these three lines are shown, the contacts 82 and 83 belonging to the last trunk line being connected together.

When the calling subscriber removes his receiver preparatory to making a call, the switch hook rises, permitting the spring 80 to engage the spring 81, whereby a circuit is closed through the line relay 16 of the line switch C. This circuit extends from ground G' through the springs 85 and 86, line conductor 90, hook switch springs 80 and 81, impulse springs 8 and 7, receiver 2, transmitter 3, line 91, springs 88 and 87 and the winding 16 to the battery lead 92, thence through battery B to ground G. The winding 16, upon energizing, attracts the armature 13, which operates to complete a circuit from ground G' through the springs 85 and 84, pull-in winding 14, auxiliary winding 17, contact point 93 and armature 32 to the battery lead 92. The winding 14, upon energizing, attracts the plunger arm 10 and the cut-off armature 12. The armature 12 operates to disconnect the line winding and ground G' from the line, while the plunger arm 10 causes the plunger to force the springs 20—27 into contact, as shown. The engagement of the springs 20 and 22 with the springs 21 and 23, respectively, extends the line conductors 90 and 91 to the selector E, whereupon its line relay 48 becomes energized over a circuit extending from ground G' through the lower winding of said relay, side switch wiper 42, springs 23 and 22, thence to and through the substation A and back over the other side of the line through the springs 20 and 21, side switch wiper 41 and the upper winding of the relay 48 to the battery lead 92. The relay 48, upon energizing, closes the circuit of the relay 49. The relay 49, upon energizing, completes a circuit from ground G' through the springs 94, 25 and 24 and the winding 15 of the line switch C to the battery lead 92. This ener-

gization of the winding 15 is for the purpose of maintaining the armature 12 and plunger arm 10 in their operated positions after the circuit of the winding 14 is broken by the falling back of the armature 13, when the line winding 16 is disconnected from the line. The auxiliary winding 17, which is energized in series with the pull-in winding 14, is short-circuited at the contact 95 when the plunger arm reaches its operated position, and is therefore energized only momentarily. This momentary energization, however, serves to maintain the armature 13 attracted for an instant after the winding 16 is deenergized, so as to insure that the circuit of the winding 14 shall not be broken before the holding winding 15 has had time to be energized. The energization of the relay 49 at the selector also extends a guarding potential from ground G' through the springs 94, 25 and 24 and over the conductor 96 to the connector private bank contacts of the calling line.

The closure of the springs 26 and 27 upon the operation of the line switch completes a circuit from ground G' through said springs 26 and 27, contact point 97, wiper 35, segment 34 and relay 98 to the battery lead 92. The relay 98, upon energizing, closes an energizing circuit through the relay 33. The relay 33, upon energizing, withdraws the pin 31 from the locking plate 30 and closes the circuit of the motor magnet 28. This circuit extends from ground G' through said magnet 28, interrupter springs 99, contact 100 and armature 32 to the battery lead 92. Since this circuit includes the interrupter springs 99, the magnet 28 will operate continuously in a manner similar to that of a buzzer to advance the plunger shaft step by step as long as the armature 32 engages the contact 100. After the plunger shaft and idle plungers have been moved a short distance, the wiper 35 passes off the contact 97, and if the next trunk line after the one seized by the switch C is idle, the relays 98 and 33 deenergize. The relay 33 being deenergized, the armature 32 will fall back and break the circuit of the magnet 28, when the next opening in the plate 30 comes directly under the pin 31 and the plungers of the idle line switches will be brought to rest in front of the corresponding trunk line. If the first trunk line after the one seized by the switch C is busy, the wiper 35 will find the corresponding contact in the master switch bank grounded. The relays 98 and 33 will therefore remain energized while the next opening in the plate 30 is passing under the pin 31, and the idle plungers will be carried past the busy trunk line to an idle one. The separation of the armature 32 from the contact point 93 while the relay 33 is energized disconnects the battery from the pull-in windings of all these line switches.

This is to prevent any line switch from being operated while its plunger is being moved to an idle trunk by the master switch.

Connection having been extended to the 5 selector E, the calling subscriber now operates his calling device for the first digit 1 of the called number. This operation of the calling device short-circuits the receiver and the transmitter by the engagement of the 10 springs 198 and 199, and momentarily separates the substation impulse springs 7 and 8 once, thereby allowing the selector line relay 48 to be momentarily deenergized. The relay 49, being slow acting, does not have time 15 to deenergize during the momentary interruption of its circuit by the relay 48. The deenergization of the relay 48 therefore results in the closure of a circuit from ground G⁵ through the spring 102 and its back contact spring 103 and its front contact, relay 50, vertical magnet 39 and the side switch wiper 44 to the battery lead 92. The vertical magnet, upon energizing, raises the switch wipers one step to a position opposite 20 the first level of bank contacts. The relay 50, which is energized in series with the vertical magnet 39, is a slow acting relay and deenergizes shortly after the circuit of said magnet is broken. If more than one 25 impulse had been transmitted through the vertical magnet, the relay 50 would not have deenergized until after the last impulse had been delivered. The relay 50, upon energizing, completes a circuit from ground G⁵ 30 through the springs of said relay and through the private magnet 45 to the battery lead 92. The private magnet 45, upon energizing and deenergizing, causes the side switch to pass from first to second position. 35 The side switch wiper 44, in second position, disconnects the battery from the vertical magnet 39 and completes a circuit from ground G² through the interrupter springs 104, rotary magnet 40, relay 51 and the side 40 switch wiper 44 to the battery lead 92. Since this circuit includes the interrupter springs 104, the rotary magnet will operate 45 in a manner similar to that of a buzzer to rotate the switch shaft step by step as long 50 as the side switch remains in second position. If the first trunk line in the first level is idle, the side switch will be tripped from second to third position by the action of the armature of the rotary magnet upon the 55 armature of the private magnet the first time the rotary magnet is energized, and the wipers 36, 37 and 38 will come to rest upon the contacts of said first trunk line. If this first trunk line is in use, however, 60 having been seized over its multiple contacts by some other selector similar to the selector E, the wiper 37 will find the contact which it engages provided with a guarding ground potential. An energizing circuit will therefore be completed from said guarded contact 65

through the wiper 37, side switch wiper 43 (in second position) and the private magnet 45 to the battery lead 92. The private magnet, being energized, locks the side switch in second position and the rotary magnet 70 will continue to advance the wipers step by step until the private wiper 37 engages the non-grounded contact of an idle line, whereupon the private magnet 45 will deenergize and permit the side switch to pass to third 75 position. The side switch wipers 41 and 42, in passing from second to third position, disconnect the line relay 48 from the line and extend the connection through the wipers 36 and 38 and over the conductors 65 80 and 66 to the selector F (Fig. 2). The line relay 62 of the selector F thereupon becomes energized over a circuit extending from ground G⁶ through the lower winding of said relay, springs 109 and 108, conductor 85 66, thence to and through the substation A and back over the other side of the line, trunk line conductor 65, springs 105 and 106 and the upper winding of the relay 62 through the battery lead 92. The relay 62, 90 upon energizing, completes a circuit from ground G⁷ through the spring 111 and its front contact and the relay 112 to the battery lead 92. The relay 112, upon energizing, provides a holding circuit for the relay 95 49 of the selector E to maintain said relay energized after its original energizing circuit is broken by the falling back of the relay 48 when it is disconnected from the line. This holding circuit extends from 100 ground G⁸ through the springs 115, conductor 116, contact 52, wiper 37, side switch wiper 43, spring 117 and its back contact and the relay 49 to the battery lead 92. A guarding potential is also extended from 105 ground G⁸ over the circuit just traced to the selector private bank contact 52 and thence to the corresponding contact in the banks of all the selectors which have access to this trunk line. A short interval elapses 110 between the time when the side switch of the selector E passes to third position and the time when the relay 112 of the selector F energizes to extend the guarding potential back to the private bank contacts of the 115 trunk line. During this interval the guarding potential is provided by the relay 51 of the selector E. This relay is energized in series with the rotary magnet 40 and, being 120 a slow acting relay, remains energized for a short time after the side switch has passed to third position. In its energized position the relay 51 extends a connection from ground G⁹ through the springs 118 and 117, side switch wiper 43 and the wiper 37 to 125 the selector private bank contacts. The relay 51, of course, deenergizes in time to close the holding circuit of the relay 49 before it has time to deenergize.

The subscriber at the calling substation 130

now operates his calling device for the second digit 5, thereby momentarily interrupting the circuit of the relay 62 of the selector F five times. Since the relay 112 is slow 5 acting like the relay 49 of the selector E, each time the relay 62 deenergizes a circuit is closed from ground G⁷ through the spring 111 and its back contact, spring 119 and its front contact, relay 120, vertical magnet 121 and the side switch wiper 122 to the battery 10 lead 92. The five impulses transmitted over this circuit cause the vertical magnet to raise the switch shaft five steps to raise the wipers to a position opposite the fifth level of bank 15 contacts. The relay 120, which is included in circuit in series with the vertical magnet, is a slow acting relay and remains energized during the entire time the vertical magnet is operating. In its energized position the relay 120 completes a circuit from ground G¹⁰ 20 through the spring 123 and its front contact and the private magnet 124 to the battery lead 92. When the relay 120 deenergizes after the last impulse is delivered to the vertical 25 magnet, it breaks the circuit of the private magnet 124, which thereupon deenergizes and causes the side switch to pass from first to second position. The side switch wiper 122, in passing from first to 30 second position, transfers the battery connection from the vertical magnet 121 to the rotary magnet 125. Thus, when the calling subscriber operates his calling device for the next digit 5, the operation of the line relay 35 62, in response to the impulses for said digit, transmits a series of five impulses over a circuit extending from ground G⁷ through the spring 111 and its back contact, spring 119 and its front contact, relay 120, springs 40 126, rotary magnet 125 and the side switch wiper 122 to the battery lead 92. The magnet 125, operating in response to these impulses, rotates the shaft five steps to carry the wipers 58, 59, 60 and 61 onto the first 45 trunk line of the group No. 155, which in this case is assumed to be the trunk line shown leading to the connector H. If this trunk line is idle, the relay 120 operates in response to the impulses for this digit in the 50 same manner as explained for the previous digit, to cause the private magnet to advance the side switch one step—that is, from second to third position—after the last impulse is delivered. If this trunk line had been 55 busy, however, the wiper 61 would have found the contact which it engaged provided with a guarding ground potential. This guarding potential would have provided an energizing circuit for the relay 127, said circuit 60 extending through the shaft wipers 61, side switch wiper 129 (this wiper being in second position) and the relay 127 to the battery lead 92. The relay 127, upon energizing, completes a circuit from ground G¹¹ 65 through the springs 130 and the private magnet 124 to the battery lead 92. This circuit maintains the private magnet 124 energized after the relay 120 is deenergized after the last impulse is delivered to the rotary magnet by the line 62. The private magnet 124, 70 being locked up, holds the side switch in second position, and the relay 127, being energized, the deenergization of the relay 120 completes a circuit from ground G¹⁰ through the spring 123 and its back contact, springs 75 131, springs 132, springs 126, rotary magnet 125 and the side switch wiper 122 to the battery lead 92. The rotary magnet energizes upon the completion of this circuit and operates to advance the shaft wipers one step to the next trunk line, and also completes a circuit from ground G¹² through the contact 133 and the relay 134 to the battery lead 92. The relay 134, upon energizing, interrupts the circuit of the rotary magnet at the 80 springs 132. The rotary magnet thereupon deenergizes and in turn breaks the circuit of the relay 134. The relay 134, upon deenergizing, again closes the circuit of the rotary magnet. The relay 127 will remain energized as long as the wiper 61 continues to 85 engage grounded contacts of busy trunk lines, and the rotary magnet will continue to advance the wipers step by step until the wiper 61 finds a non-grounded contact and permits the relay 127 to deenergize, or until the wipers 60 and 61 engage the contacts 82 and 83, which are connected together. These contacts 82 and 83, as has been explained, belong to the last trunk line of the 90 group No. 155. Of course, if this trunk line is idle, the contacts 82 and 83 will not be grounded and the relay 127 will deenergize and permit the wipers to come to rest thereon in the same manner as for any other idle 95 trunk line. If this trunk line is busy, however, the contact 82, as well as the contact 83, will be grounded. The ground upon the contact 83 would cause the wipers to continue their automatic rotation but for the 100 fact that the ground from the contact 82 completes a circuit extending through the wiper 60, springs 234 and 135, springs 136, relay 137 and the side switch wiper 138 to the battery lead 92. The relay 137, upon 105 energizing, breaks the circuit of the rotary magnet at the springs 126, notwithstanding the fact that the relay 127 remains energized. The wipers 58, 59, 60 and 61, therefore, come to rest upon the contacts of this 110 busy trunk line, but no connection is completed between the calling line and this trunk line because the private magnet 124 remains energized and holds the contacts 139 and 140 open. The relay 137, upon 115 energizing, forms a locking circuit for itself, independently of the contact 82. This circuit extends from ground G¹¹ through the springs 130, springs 141, 142 and 135, 136, relay 137 and the side switch wiper 138 to 120 125 130

the battery lead 92. This locking circuit is to prevent the selector F from completing connection with the trunk line in case the guarding potential is removed from the contact 82 after the selector F has attempted to make connection therewith and before the calling subscriber has hung up his receiver. The relay 137, in its energized position, also completes a connection from the busy signaling machine M' through the springs 143, condenser 64 and thence over the heavy conductors to the calling substation A, whereby the calling subscriber is given the busy signal to indicate that all of the trunk lines leading to the desired branch exchange are in use. The return circuit for the busy signaling current, after passing through the substation, is over the line conductor 91, thence through the selector E and over the trunk conductor 65 and through the upper winding of the line relay 62 of the selector F to the battery lead 92, and thence back to the busy signaling machine M'. Upon receiving the busy signal, the calling subscriber, by hanging up his receiver, releases the switches C, E and F in the same manner as when a complete connection has been completed and which will be described later.

When the wipers of the selector F come to rest upon the contacts of an idle trunk line and the private magnet 124 deenergizes, as has been explained, the side switch passes to third position and the connection with the trunk conductors 145 and 146 is completed by the closure of the contacts 139 and 140. The side switch wiper 129, upon passing to third position, extends a guarding potential from ground G¹³ through said wiper 129 and the private wiper 61 to the private bank contact of the seized trunk line in the banks of all the switches which have access thereto. The side switch wiper 147, upon reaching third position, completes a bridge across the trunk conductors 145 and 146, whereupon the line relay 148 of the connector H becomes energized over the circuit extending from ground G¹⁴ through the lower winding of said relay, springs 149 and 150, conductor 146, wiper 58, side switch wiper 147, impedance coil 151, winding 69, springs 152, wiper 59, conductor 145, springs 153 and 154 and the upper winding of the relay 148 to the battery lead 155. The relay 148, upon energizing, completes the circuit of the relay 156. At the selector F the current flowing through the winding 69 of the relay 67 is opposed by a current flowing through the winding 68 over a circuit extending from ground G¹⁵ through the springs 157 and the winding 68 to the battery lead 92, and the relay is not operatively energized. The circuit of the winding 68 is closed as soon as the switch shaft leaves its normal position, but, as has been explained, the relay 67 can not be operated by

the energization of one winding alone. When the substation calling device is operated for the fourth digit, the circuit of the line relay 62 of the selector F is again broken twice momentarily. The separation 70 of the springs 152 by the deenergization of the relay 62 at this time opens the bridge across the trunk conductors 145 and 146, thereby breaking the energizing circuit of the relay 148 of the connector H. The relay 75 148, upon deenergizing, completes a circuit from ground G¹⁶ through the spring 158 and its back contact, spring 159 and its front contact, relay 160, vertical magnet 73 and the side switch wiper 161 to the battery lead 80 155. Since the digit called is 2, the vertical magnet receives two impulses over this circuit and operates to raise the switch shaft and wipers two steps. The relay 160, being a slow acting relay, operates to maintain 85 the circuit from ground G¹⁷ through the springs 162 and 163 and the private magnet 75 to the battery lead 155 closed while the vertical magnet is operating. After the last impulse is delivered to the vertical 90 magnet, the relay 160 deenergizes and in turn permits the private magnet 75 to deenergize to allow the side switch to pass to second position. At the selector F, each time the relay 62 deenergizes to repeat an 95 impulse to the relay 148 of the connector, a circuit is closed from ground G⁷ through the spring 111 and its back contact, spring 119 and its front contact, relay 120, relay 166 and the side switch wiper 122 to the 100 battery lead 92. The energization of the relay 120 at this time is functionless and causes the private magnet to open the contacts 139 and 140 while impulses are being repeated over the trunk conductors 145 and 105 146. This operation of the private magnet has no effect on the side switch because it has reached the limit of its travel. The relay 166, being slow acting, remains in its energized position during the entire time 110 the relay 62 is operating in response to the impulses received from the substation, and in its energized position the relay 166 short-circuits the impedance coil 151 and the winding 69 of the relay 67 so as to remove the 115 resistance from the circuit of the connector line relay while it is being operated.

When the substation calling device is operated for the last digit 0, the line relay 62 of the selector F operates in response to 120 the impulses received from the substation to repeat ten impulses to the line relay 148 of the connector H. Each time the relay 148 deenergizes in response to these impulses it completes a circuit from ground G¹⁸ through the springs 158 and 159, relay 160, springs 167, rotary magnet 74 and the side switch wiper 161 to the battery lead 155. The rotary magnet 74 therefore operates to advance the wipers 70, 71 and 72 ten steps onto 125 130

the contacts of the desired line. If this line is idle, the relay 160 operates in the same manner as for the previous digit, to cause the private magnet 75 to advance the side switch 5 to third position after the last impulse is received. The side switch, upon passing to third position, completes the connection with the called line and said line is protected by a guarding potential extending from ground 10 G¹⁸ through the side switch wiper 168 and the shaft wiper 72 through the connector private bank contacts of the called line. From the wiper 72 a circuit also extends through the cut-off winding 169 of the line switch C' to the battery lead 155. The winding 169, upon energizing, attracts the armature 170, which disconnects the switch C' 15 from the called line and closes the contact 171 in the talking circuit. The side switch 20 wiper 161, upon passing to third position, completes a circuit from ground G¹⁸ through the interrupter 173, ringing relay 76, springs 174 and 175 and the side switch wiper 161 to the battery lead. The relay 76, upon 25 energizing, disconnects the calling line from the called line and connects the ringing current generator L with the called line to signal the called subscriber. Since the circuit of the ringing relay includes the interrupter 173, said relay is energized only intermittently so as not to ring the called subscriber continuously. When the called subscriber removes his receiver, or as soon 30 thereafter as the ringing relay 76 deenergizes, if it happens to be energized at the time, the called substation is provided with talking current over a circuit extending from ground G¹⁸ through the side switch wiper 168, lower winding of the relay 176, 35 ringing relay springs 177 and 178, side switch wiper 179, line 180, thence to and through the substation A' and back over the line 181, through the contact 171, wiper 70, springs 182^a and 183^a, springs 184, upper 40 winding of the relay 176 and the side switch wiper 161 to the battery lead 155. The relay 176, upon energizing, completes a circuit extending from ground G¹⁸ through the side switch wiper 168, relay 182 and springs 183 45 to the battery lead 155. The relay 182, upon energizing, breaks the circuit of the ringing relay 76 and forms a locking circuit for itself by way of the springs 184 and 175 and the side switch wiper 161 to the battery lead 50 155. The shifting of the springs 150 and 153 out of engagement with their back contacts and into engagement with their front contacts by the energization of the relay 182 transposes the connections between the 55 windings of the relay 148 and the trunk conductors 145 and 146. This transposition reverses the current in the winding 69 of the relay 67 at the selector F. The relay 69 now assists the winding 68 and the relay 67 is 60 operatively energized. The relay 67, upon 65

energizing, transposes the connections between the windings of the relay 62 and the trunk conductors 65 and 66, thereby reversing the direction of the current flowing in the calling line. Although this reversal of 70 current in the calling line has no particular function in the system as shown herein, it is often used for the purpose of operating call registers or supervisory signals in a semi-automatic connection. 75

Upon the termination of the conversation, the entire connection is released by the hanging up of the receiver at the calling substation. When the receiver is hung up, the circuit of the line relay 62 of the selector F is 80 broken. The relay 62, upon deenergizing, destroys the energizing circuit of the relay 112, as well as that of the connector line relay 148. The relay 112, upon deenergizing, completes a circuit extending from ground G⁷ 85 through the spring 111 and its back contact, spring 119 and its back contact, springs 186 and the release magnet 187 to the battery lead 92. The magnet 187, upon energizing, causes the shaft and the side switch of the selector F to be restored to normal position, and when the switch shaft reaches its lowest position the circuits of the release magnet 187 and winding 68 are broken at the springs 186 and 167. The relay 112, upon deenergizing, also opens the holding circuit of the release relay 49 of the first selector E. The relay 49, upon deenergizing, completes the circuit of the release magnet 46 and also breaks the holding circuit of the winding 15 100 of the line switch C. The magnet 46, upon energizing, releases the selector E, and the winding 15, upon deenergizing, permits the plunger of the line switch to be restored to its normal position. The circuit of the magnet 105 46 is broken by the selector shaft when it reaches its lowest position and separates the springs 47. When the relay 148 of the connector H deenergizes upon the interruption of its circuit by the relay 62 of the selector F, a circuit is closed from ground G¹⁸ through the spring 158 and its back contact, spring 159 and its back contact, release magnet 188 110 and the springs 189 to the battery lead 155. The magnet 188, upon energizing, releases 115 the connector switch.

In the foregoing it has been assumed that the called line was idle when the connector H made connection therewith. If a line is busy it has a guarding ground potential 120 upon its connector private bank contact, and when the wiper 72 is rotated onto said contact, this potential is extended through the wiper 72, side switch wiper 168 (which is then in second position), springs 189^a and 190 and the relay 191 to the spring 192 of the private magnet relay 160. There being a ground potential upon the spring 192, the private magnet 75 does not deenergize when the relay 160 deenergizes after the last im- 125 130

- pulse is delivered to the rotary magnet, but remains energized in series with the relay 191. The relay 191, upon energizing, forms a locking circuit for itself extending from 5 ground G²⁰ by way of the springs 193, 194 and 190 so as to prevent said relay from de-energizing in case the guarding potential should be removed from the private bank contacts. In its energized position the relay 10 191 also completes a connection from the busy signaling machine M through the springs 195, contact 196, side switch wiper 179, condenser 79 and thence over the heavy conductors to the calling substation. It 15 will thus be seen that if a busy line is called, the calling subscriber is given the busy signal and no connection is completed with the busy line because the private magnet 75 does not deenergize after the last digit is called, 20 and, therefore, the connection is maintained open on one side at the springs 184 and on the other side at the said switch wiper 179, which wiper remains locked in second position.
- 25 As shown herein, the trunk lines leading from the selector-repeater F lead to connector switches in the branch exchange. It will be evident that such trunk lines might terminate in selector switches which have access to a plurality of connectors. The subscribers' line switches C' in the branch exchange may have access to selector switches similar to the selector E (Fig. 1), by means of which the branch exchange subscribers 30 35 may select trunk lines leading either to the main exchange or to connector switches in their own branch exchange.
- While I have illustrated and described my invention in connection with a particular type of automatic telephone system, it is to be understood that I do not wish to be limited to such a system, as it is obvious that if desired the connection between a calling and a called subscriber's line could be established partly manually and that other substitutions and changes could be made without departing from the spirit of my invention.
- What I claim as my invention is:—
1. In an automatic telephone system, a main exchange, a plurality of private branch exchanges, a group of trunk lines extending from said main exchange to each of said branch exchanges, automatic progressively movable switches at said branch exchanges 40 45 50 55 60 65 in which said trunk lines terminate, an automatic switch at the main exchange having a plurality of contacts arranged in different levels, and a plurality of groups of said trunk lines terminating in a single level of said switch, and means for operating said progressively movable switches over said trunk lines through said automatic switch.
  2. In an automatic telephone system, a main exchange, a plurality of private branch exchanges, a group of trunk lines extend- 65
  - ing from said main exchange to each of said branch exchanges, automatic progressively movable switches at said branch exchanges in which said trunk lines terminate, an automatic switch at the main exchange having a 70 plurality of contacts arranged in different levels, a plurality of groups of said trunk lines terminating in a single level of said switch, means for operating said progressively movable switches over said trunk 75 lines through said automatic switch, and means for controlling said switch over two sides of a line circuit in series.
  3. In a telephone system, a main exchange, a plurality of private branch exchanges, a 80 group of trunk lines extending from said main exchange to each of said branch exchanges, a connector switch at said branch exchanges in which said trunk lines terminate for connecting with the called subscriber's line, a selector switch at said main exchange, said selector switch having contacts arranged in a plurality of main groups, a plurality of groups of said trunk lines terminating in a single main group of said 85 90 contacts of said switch, and means controlled by said switch for repeating impulses to control the operation of said connector switches.
  4. In a telephone system, a main exchange, a plurality of groups of private branch exchanges, a group of trunk lines extending from said main exchange to said branch exchanges, a connector switch at said branch exchanges in which said trunk lines terminate for connecting with the called subscriber's line, a selector switch at said main exchange, said selector switch having contacts arranged in a plurality of main groups, a plurality of groups of said trunk lines terminating in a single main group of contacts 95 100 105 of said switch, means controlled by said switch for repeating impulses to control the operation of said connector switches, and means for controlling said switches over two sides of a line circuit in series.
  5. In a telephone system, an automatic switch, trunk lines divided into groups and sub-groups, said switch having one motion to select groups and a second motion to select a sub-group and then select an idle trunk line in said selected sub-group, and means in said switch for repeating impulses over said selected trunk.
  6. In a telephone system, an automatic switch, trunk lines divided into groups and sub-groups, said switch having one motion to select groups and a second motion to select a sub-group and then select an idle trunk line in said selected sub-group, means for controlling said switch over two sides of 110 115 120 125 130 a line circuit in series, and means in said switch for repeating impulses over said selected trunk.
  7. In a telephone system, a main exchange, a private branch exchange, a plurality of

groups of trunk lines extending from said main exchange to said branch exchange, a trunk selector at said main exchange, said selector having one motion to select groups and a second motion to select sub-groups and then select an idle trunk in a selected sub-group, and means in said switch for repeating impulses over said selected trunk.

8. In a telephone system, a main exchange, a private branch exchange, a plurality of groups of trunk lines extending from said main exchange to said branch exchange, a trunk selector at said main exchange, said selector having one motion to select groups and a second motion to select sub-groups and then select an idle trunk in a selected sub-group, means for controlling said switch over two sides of a line circuit in series, and means in said switch for repeating impulses over said selected trunk.

9. In a telephone system, a plurality of lines divided into groups, a selector switch having motion in one plane to select groups and rotary motion to find a line in a selected group, a line relay, a slow-acting relay, means for energizing said slow-acting relay when said line relay is energized, means for partly rotating said switch when said slow-acting relay is energized and completing the rotation of said switch when said slow-acting relay is deenergized, and means in said switch for repeating impulses over said selected trunk.

10. In a telephone system, a plurality of lines divided into groups, a selector switch having one motion to select groups and rotary motion to find a line in a selected group, a line relay, a slow-acting relay, means for energizing said slow-acting relay, and then deenergizing said relay when said line relay is energized, means for partly rotating said switch when said slow-acting relay is energized and completing the rotation of said switch when said slow-acting relay is deenergized, and means in said switch for repeating impulses over a selected line.

11. In a telephone system, a plurality of lines divided into groups, a selector switch having one motion to select groups and rotary motion to find a line in a selected group, a line relay, a slow-acting relay, means for energizing said slow-acting relay when said line relay is energized, means for partly rotating said switch when said slow-acting relay is energized and completing the rotation of said switch when said slow-acting relay is deenergized, and means controlled by said line relay for repeating impulses over the selected line.

12. In a telephone system, a plurality of lines divided into groups, a selector switch having one motion to select groups and rotary motion to find a line in a selected group, a line relay, a slow-acting relay,

means for energizing said slow-acting relay, and then deenergizing said relay when said line relay is energized, means for partly rotating said switch when said slow-acting relay is energized and completing the rotation of said switch when said slow-acting relay is deenergized, and means controlled by said line relay for repeating impulses over the selected line.

13. In a telephone system, an automatic switch, a bank of line contacts and two banks of private contacts, a private wiper adapted to engage each of said private contacts, a group of trunk lines having a third conductor connected with the corresponding contact in one of said private banks, and means whereby a guarding potential upon one of said private contacts will cause the wipers to be rotated past the corresponding trunk, while a guarding potential upon both private contacts will cause the wipers to stop upon said trunk.

14. In a telephone system in which the terminals of the trunk lines are arranged in groups and in which the trunks in each group are further arranged in sub-groups, a line, conductors for said line, a circuit closer for said line, a propelling mechanism for advancing said circuit closer to a group of trunks, and for thereafter advancing the circuit closer to a sub-group of trunks, test circuits for testing and for making the trunks busy in the sub-group, means individual to said circuit closer controlled by said test circuits when all the trunks are busy for rendering said mechanism inoperative, said test circuits being independent of the conductors of said line, other lines, and means for extending a connection from any one of said trunks to any one of said other lines.

15. In a telephone system in which the terminals of the trunk lines are arranged in groups and in which the trunks in each group are further arranged in sub-groups, a line, conductors for said line, a circuit closer for said line, a propelling mechanism for advancing said circuit closer to a group of trunks, and for thereafter advancing the circuit closer to a sub-group of trunks, test circuits for testing and for making the trunks in the sub-group busy, means individual to said circuit closer controlled when all of the trunks are busy for rendering the said mechanism inoperative, a release device associated with said mechanism for restoring the said mechanism to operative condition, said test circuits being independent of the conductors of said line, other lines, and means for extending a connection from any one of said trunks to any one of said other lines.

16. In a telephone system in which the terminals of the trunk lines are arranged in groups and in which the trunks in each

- group are further arranged in sub-groups, a line, conductors for said line, a circuit closer for said line, a propelling mechanism for advancing said circuit closer to a group 5 of trunks, and for thereafter advancing the circuit closer to a sub-group of trunks, test circuits for testing and for making the trunks busy in the sub-group, means individual to said circuit closer controlled by 10 said test circuits when all the trunks are busy for rendering said mechanism inoperative, a release device associated with said mechanism for restoring the said mechanism to operative condition, said test circuits being independent to the conductors of said 15 line, other lines, and means for extending a connection from any one of said trunks to any one of said other lines.
17. In a telephone system, an automatic progressively movable switch, trunk lines accessible to said switch, said trunk lines divided into groups, a controlling relay for said switch, an operating mechanism controlled by said relay to elect a group of said 20 trunks, the elected group divided into sub-groups of trunks, said mechanism controlled by said relay for electing a sub-group of trunks, busy test circuits associated with the trunks of said sub-group for automatically 25 operating said mechanism until an idle trunk in said sub-group is found, an auxiliary relay in said switch and an auxiliary circuit associated with said sub-group for operating said relay to render the said 30 mechanism inoperative to select trunks if all the trunks of the sub-group are busy, other lines, and means for extending a connection from any one of said trunks to any one of said other lines.
18. In a telephone system, an automatic progressively movable switch, trunk lines accessible to said switch, said trunk lines divided into groups, a controlling relay for said switch, an operating mechanism controlled by said relay to elect a group of 35 said trunks, the elected group divided into sub-groups of trunks, said mechanism controlled by said relay for electing a sub-group of trunks, busy test circuits associated with the trunks of said sub-group for automatically 40 operating said mechanism until an idle trunk in said sub-group is found, an automatic switch associated with the selected trunk, a control circuit for said 45 last switch comprising a section individual to the first switch and under the control of said relay, and a section individual to the selected trunk, said mechanism operating to bring the two together when an 50 idle trunk is found, whereby the switch in the selected trunk may be controlled by the said relay.
19. In a telephone system, a line, an impulse sender associated with said line, an 55 automatic progressively movable switch for said line, trunk lines associated with said switch, said trunk lines divided into groups, an operating mechanism for said switch, a control relay associated with said line to respond to said impulse sender, said mechanism controlled by said relay in response to said sender to elect a group of trunks and also to elect a sub-group of trunks, an auxiliary circuit for energizing said mechanism after the impulse sender has ceased sending 60 impulses to automatically operate to select an idle trunk in the elected sub-group, means for maintaining said auxiliary circuit inoperative as long as the switch is operating to elect a sub-group, other lines, and means for extending a connection from any one of said trunks to any one of said other lines.
20. In a telephone system, a line, an impulse sender associated with said line, an automatic progressively movable switch for said line, trunk lines associated with said switch, said trunk lines divided into groups, an operating mechanism for said switch, a control relay associated with said line to respond to said impulse sender, said mechanism controlled by said relay in response to said sender to elect a group of trunks and also to elect a sub-group of trunks, an auxiliary circuit for energizing said mechanism after the impulse sender has ceased sending 65 impulses to automatically operate to select an idle trunk in the elected sub-group, means for maintaining said auxiliary circuit inoperative as long as the switch is operating to elect a sub-group, other lines, and means for extending a connection from any one of said trunks to any one of said other lines.
21. In a telephone system, a line, an impulse sender associated with said line, an automatic progressively movable switch for said line, trunk lines associated with said switch, said trunk lines divided into groups, an operating mechanism for said switch, a control relay associated with said line to respond to said impulse sender, said mechanism controlled by said relay in response to said sender to elect a group of trunks and also to elect a sub-group of trunks, an auxiliary circuit for energizing said mechanism after the impulse sender has ceased sending 70 impulses to automatically operate to select an idle trunk in the elected sub-group, and a slow-acting device for maintaining said auxiliary circuit inoperative as long as the switch is operating to elect a sub-group, other lines, and means for extending the connection from any one of said trunks to any one of said other lines.
22. In a telephone system in which the terminals of the trunk lines are arranged in groups and in which the trunks in each group are further arranged in sub-groups, a line, a circuit closer for said line, a pro- 75

- propelling mechanism for advancing said circuit closer to a group of trunks, and for thereafter advancing the circuit closer to a sub-group of trunks, means for making a 5 trunk busy in the sub-group, said mechanism controlled by said means to automatically advance the circuit closer in the sub-group until a non-busy trunk is found, means comprising said circuit closer for connecting the line and the non-busy trunk, an inductive device associated with the circuit closer for dividing the established circuit between the said line and trunk into two sections, an impulse sender associated with 10 the line side of the division, and an impulse receiving and repeating device associated with the circuit closer and responsive to the impulse sender to repeat impulses to the trunk side of the division.
- 15 23. In a telephone system in which the terminals of the trunk lines are arranged in groups and in which the trunks in each group are further arranged in sub-groups, a line, a circuit closer for said line, a propelling mechanism for advancing said circuit closer to a group of trunks, and for thereafter advancing the circuit closer to a sub-group of trunks, means for making a 20 trunk busy in the sub-group, said mechanism controlled by said means to automatically advance the circuit closer in the sub-group until a non-busy trunk is found, means comprising said circuit closer for connecting the line and the non-busy trunk, an inductive 25 device associated with the circuit closer for dividing the established circuit between the said line and trunk into two sections, an impulse sender associated with the line side of the division, and an impulse receiving 30 and repeating device associated with the circuit closer and responsive to the impulse sender to repeat impulses to the trunk side of the division, said impulse receiving and repeating device having a line relay connect- 35 ed with the line for receiving the impulses from the impulse sender over both sides of the line in series.
- 40 24. In a telephone system in which the terminals of the trunk lines are arranged in groups and in which the trunks in each group are further arranged in sub-groups, a line, a circuit closer for said line, a propelling mechanism for advancing said circuit closer to a group of trunks, and for there- 45 after advancing the circuit closer to a sub-group of trunks, means for making a trunk busy in the sub-group, said mechanism controlled by said means to automatically advance the circuit closer in the sub-group until a non-busy trunk is found, means comprising said circuit closer for connecting the line and the non-busy trunk, an inductive device associated with the circuit closer for dividing the established circuit between the 55 said line and trunk into two sections, an im-

pulse sender associated with the line side of the division, and an impulse receiving and repeating device associated with the circuit closer and responsive to the impulse sender to repeat impulses to the trunk side of the 70 division, said impulse receiving and repeating device having a line relay connected with the line for receiving the impulses from the impulse sender over both sides of the line in series and for repeating said impulses to the 75 trunk.

25. In a telephone trunking system in which the terminals of the trunk lines are arranged in groups and in which each group is further arranged into sub-groups, a line, 80 conductors for said line, an automatic progressively movable switch, said switch controlled over the line to elect a group of trunks and thereafter to elect a sub-group of trunks therein, test circuits for said trunks 85 and switch, means in said test circuits individual to said switch for controlling the switch to insure its advancement from busy trunk to busy trunk automatically until an idle trunk is found, said test circuits being 90 independent of the conductors of said line, and an auxiliary circuit whereby if all the trunks in the sub-group are busy the switch is prevented from passing to the next sub-group, other lines, and means for extending 95 a connection from any one of said trunks to any one of said other lines.

26. In a telephone trunking system in which the terminals of the trunk lines are arranged in groups and in which each group is further arranged into sub-groups, a line, 100 conductors for said line, an automatic progressively movable switch, said switch controlled over the line to elect a group of trunks and thereafter to elect a sub-group of trunks therein, test circuits for said trunks 105 and switch, means in said test circuits individual to said switch for controlling the switch to insure its advancement from busy trunk to busy trunk automatically until an 110 idle trunk is found, said test circuits being independent of the conductors of said line, and an auxiliary circuit whereby if all the trunks in a sub-group are busy the mechanism for advancing the switch is rendered 115 inoperative to prevent the switch from passing to another sub-group, other lines, and means for extending a connection from any one of said trunks to any one of said other lines.

27. In a telephone trunking system in which the terminals of the trunk lines are arranged in groups and in which each group is further arranged into sub-groups, a line, 120 an automatic progressively movable switch, 125 said line individual to said switch, said switch controlled over two sides of the line in series, to elect a group of trunks and thereafter to elect a sub-group of trunks therein, test circuits for said trunks and 130

switch, for controlling the switch to insure its advancement from busy trunk to busy trunk automatically until an idle trunk is found, other lines, and means for extending 5 connection from any one of said trunk lines to any one of said other lines.

28. In a telephone trunking system in which the terminals of the trunk lines are arranged in groups and in which each group 10 is further arranged into sub-groups, a line, an automatic progressively movable switch, said line individual to said switch, said switch controlled over two sides of the line in series, to elect a group of trunks and 15 thereafter to elect a sub-group of trunks therein, test circuits for said trunks and switch, for controlling the switch to insure its advancement from busy trunk to busy trunk automatically until an idle trunk is 20 found, and an auxiliary circuit whereby if all the trunks in the sub-group are busy the switch is prevented from passing to the next sub-group, other lines, and means for extending the connection from any one of said 25 trunks to any one of said other lines.

29. In a telephone trunking system in which the terminals of the trunk lines are arranged in groups and in which each group is further arranged into sub-groups, a line, 30 an automatic progressively movable switch, said line individual to said switch, said switch controlled over two sides of the line in series, to elect a group of trunks and thereafter to elect a sub-group of trunks 35 therein, test circuits for said trunks and switch, for controlling the switch to insure its advancement from busy trunk to busy trunk automatically until an idle trunk is found, and an auxiliary circuit whereby if 40 all the trunks in a sub-group are busy the mechanism for advancing the switch is rendered inoperative to prevent the switch from passing to another sub-group, other lines, and means for extending the connection 45 from any one of said trunks to any one of said other lines.

30. In a telephone system, a plurality of trunk lines, a selector switch having a contact arm adapted to connect with any one 50 of said trunks, means for operating said arm, means whereby said arm will not stop upon certain of said trunks unless said trunks are idle, means whereby said arm will stop upon other of said trunks whether 55 they are idle or busy, means for preventing the establishment of a circuit over said last-mentioned trunks if they are busy, all of said means having magnets all of which are always energized by a current flow in the 60 same direction, other lines, and means for extending a connection from any one of said trunks to any one of said other lines.

31. In a telephone system, a plurality of subscribers' lines, means including a group 65 of trunks for establishing a connection be-

tween a calling and a called subscriber's line, an automatic switch for connecting with said trunks, means whereby said switch will not stop upon certain of said trunks unless said trunks are idle, means whereby said 70 switch will stop upon one of said trunks whether it is idle or busy, means for giving a busy signal in case said switch stops upon a trunk that is busy, all of said means having magnets all of which are always energized by a current flow in the same direction, other lines, and means for extending a connection 75 from any one of said trunks to any one of said other lines.

32. In a telephone system, a plurality of 80 trunk lines, a selector switch adapted to connect with any one of said trunks, means whereby said switch will not stop upon certain of said trunks unless said trunks are idle, means whereby said switch will stop 85 upon other of said trunks whether they are idle or busy, all of said means having magnets all of which are always energized by current flow in the same direction, other lines, and means for extending a connection 90 from any one of said trunks to any one of said other lines.

33. In a telephone system, an automatic switch, trunk lines accessible to said switch divided into groups and sub-groups, means 95 for operating said switch to select a desired group and sub-group, automatic means for operating said switch to select an idle trunk in a selected sub-group, a busy test relay individual to said switch and a circuit for said 100 relay including a movable contact of said switch closed only when the switch in its automatic operation arrives at the last trunk in the sub-group.

34. In a telephone system, an automatic 105 switch, trunk lines accessible to said switch divided into groups and sub-groups, means for operating said switch to select a desired group and sub-group, automatic means for operating said switch to select an idle trunk 110 in a selected sub-group, busy signaling mechanism, and separate test circuits for controlling said automatic means and said signaling mechanism.

35. In a telephone system, an automatic 115 switch, trunk lines accessible to said switch divided into groups and sub-groups, means for operating said switch to select a desired group and sub-group, automatic means for operating said switch to select an idle trunk 120 in a selected sub-group, busy signaling mechanism, and separate test circuits for controlling said automatic means and said signaling mechanism, means for closing one of said test circuits to test each trunk in the 125 group and means for closing the other test circuit to test only the last trunk in the group.

36. In a telephone system, an automatic switch, trunk lines accessible to said switch 130

divided into groups and sub-groups, means for operating said switch to select a desired group and a desired sub-group in the selected group, automatic means for operating said switch to pass over busy trunk lines in the selected sub-group, a grounded battery, a control relay connected to the ungrounded pole of said battery, a test terminal for the last 5 trunk in the selected sub-group grounded if said trunk is busy, and a circuit for said relay including said ground connection closed by the switch when it reaches said last trunk, whereby the said relay is operated to stop said switch.

37. In a telephone system, an automatic switch, trunk lines accessible to said switch divided into groups and sub-groups, means for operating said switch to select a desired 10 group and sub-group, test terminals for said trunk lines, means for connecting said terminals to ground when the corresponding trunks are busy, a grounded battery, control mechanism in said switch connected to the 15 ungrounded pole of said battery, circuit connections established upon the selection of a sub-group between said mechanism and successive ones of said test terminals, whereby said mechanism is operated by current from the ground connections on busy test terminals to control said switch to select an idle 20 trunk and in case all the trunks are busy to stop said switch on the last trunk and means effective in the latter instance for transmitting a busy signal to the calling subscriber.

25

30

and in case all the trunks are busy to stop said switch on the last trunk.

38. In a telephone system, an automatic switch, trunk lines accessible to said switch 35 divided into groups and sub-groups, subscriber controlled means for operating said switch to select a desired group and sub-group, test terminals for said trunk lines, means for connecting said terminals to 40 ground when the corresponding trunks are busy, a grounded battery, control mechanism in said switch connected to the ungrounded pole of said battery, circuit connections established upon the selection of a 45 sub-group between said mechanism and successive ones of said test terminals, whereby said mechanism is operated by current from the ground connections on busy test terminals to control said switch to select an idle 50 trunk and in case all the trunks are busy to stop said switch on the last trunk and means effective in the latter instance for transmitting a busy signal to the calling subscriber.
